United States Patent Office

Des. 186,491
Patented Nov. 3, 1953

186,491

ADVERTISING SIGN

Arthur W. F. K. Wilson, Richmond Hill, Ontario, Canada

Application March 28, 1958, Serial No. 50,221

Term of patent 14 years

(Cl. D1—12)

FIG. 1

FIG. 3

The dominant features of my design reside in the full line portions of the drawing.

I claim:

The ornamental design for an advertising sign, as shown and described.
